E. JOSEPH KANABAY, OF CHICAGO, ILLINOIS, ASSIGNOR TO LEON BENOIT, OF CHICAGO, ILLINOIS

EGG CARTON FILLER MACHINE

Application filed April 8, 1929. Serial No. 353,646.

This invention relates to egg carton filler machines, and its principal object is to provide an automatic machine for operating on long sheets of cardboard or other filler material, and forming from said sheets notched strips that are assembled in the machine in the form of a filler for cartons and having cells spaced apart by interlocking walls. Another object of the invention is to provide a machine entirely automatic in its operation and acting to form the necessary notches in the edges of the material for obtaining the interlocking condition between the walls, and thereafter slitting or cutting the material into the required number of pieces to form a complete filler and assembling the pieces in interlocked condition.

Another object is to provide an automatic machine for producing egg carton fillers composed of interlocked longitudinal walls and cross walls and arranged to operate upon two long sheets or strips of cardboard or other filler material, moved parallel with each other part way through the machine, notching the sheets, slitting one of the sheets lengthwise to form strips and cutting the other sheet transversely thereof to form cards or other strips and thereafter assembling the two sets of notched pieces into a complete filler having interlocked walls. Another object is to provide an automatic machine of rugged and substantial construction having a capacity for turning out a great number of completed articles during a given time.

With these and other objects and advantages in view, this invention consists in a carton filler machine embodying notching mechanism, strip feeding mechanism, strip slitting mechanism, and assembling mechanism for assembling the notched pieces into a carton filler having notched interlocked walls. It further consists in a carton filler machine having mechanism whereby both of the long sheets are fed part way through the machine in parallel relation, one of the sheets being cut into strips or cards extending crosswise of the sheet, and the other sheet slit lengthwise thereof into separate strips, together with means for turning the strips of one set into parallel relation to each other,

and other means for turning the cards or strips of the other set into parallel relation at right angles to the strips of the first mentioned set, and finally assembling the two sets of notched strips to form a carton filler having interlocked walls. 55

The invention further consists in the several novel features of construction, arrangement and combination of parts hereinafter fully set forth and more particularly pointed out in the appended claims. 60

The invention is clearly illustrated in the drawings accompanying this specification in which—

Figure 1 is a plan of the receiving and 65 punching end of the machine with certain portions broken away;

Fig. 1^a is a plan of the assembling end of the machine;

Fig. 2 is a view, partly in side elevation 70 and partly in vertical longitudinal section, through the receiving and punching end of the machine, the section being taken on the line 2—2 of Fig. 1;

Fig. 3 is a view, partly in side elevation 75 and partly in vertical longitudinal section, of certain cam and cam actuating mechanism for the strip feeders and for actuating the assembling mechanism, the section being taken on the line 3 of Fig. 1;

- Fig. 23 is a detail vertical cross section taken on the line 23 of Fig. 21, and illustrating certain rocking strip guiding members of the assembling mechanism;
- Fig. 24 is a view similar to Fig. 23, but showing the strip guiding members in a different position;
- Fig. 25 is a perspective view of the strip guiding members seen in Figs. 23 and 24;
- Fig. 26 is a fragmental side elevation, partly in vertical section, of one of the strip guiding members seen in Figs. 23, 24 and 25, the line of section being indicated at 26 in Fig. 25;
- Fig. 27 is an end elevation of the upper and lower members of the assembling mecha-
- nism illustrating the parts as they appear immediately prior to the final assembling operation;
- Fig. 28 is a side elevation, partly in section, of the mechanism seen in Fig. 27;
- Fig. 29 is a perspective view of a certain locking dog actuating bar;
- Fig. 30 is a side elevation of a certain justifying mechanism for the card grippers;
- Fig. 31 is a detail side elevation of a locking dog actuating cam;
- Fig. 32 is a detail vertical cross section through the locking jaws of one of the gripper heads taken on the line 32—32 of Fig. 17, and showing the same in the position occupied when the jaws are being opened to release the completed filler; and
- Fig. 33 is a detail vertical longitudinal section taken on the line 33 of Fig. 1^a, showing a detent or dog used for preventing retrograde movement of one of the sheets of filler material.
- The machine shown in the accompanying drawings illustrates one embodiment of the present invention, and will be described in detail in this specification. In order that the mechanism and the operations of the various parts thereof in producing the notched pieces and assembling them may be clearly understood, I shall first describe the notched pieces themselves and the filler formed thereby.
- Referring first to Figs. 5 to 7, inclusive, two series of interlocked notched cardboard pieces *a* and *b* comprise the filler formed by the machine. For convenience, the pieces *a* will be hereinafter designated as "strips" and the pieces *b* as "cards". The strips *a* have oppositely disposed notches *a'* and *a''* punched out of the edge portions, thereby leaving web portions *a³* between the notches. The end notches are placed in close proximity to the end edges of the strip and all of the notches are spaced equi-distantly. The cards *b* have notches *b'* extending inward from one of their edges, which notches receive the web portions *a³* of the strips *a* in the finished filler.
- The entrances to the notches *b'* are preferably tapered, as seen in Fig. 6, to facilitate the insertion of the strips *a* into the notches *b'* during the assembling operation of the machine, and one side edge of each notch *b'* is formed with a shoulder *b²* adjacent the edge of the strip, which shoulder engages with the end edge of the notch *a²* of the strip *a* when the strips are completely assembled, thereby forming an interlocking connection between the intersecting strips and cards and preventing any possible disconnection between them. The opposite edge of each notch *b'* is formed with two oppositely inclined edge portions that provide a tongue *b³* which enters the space above the shouldered portion *b²* of the notch and acts to hold the web portions *a³* of the strip *a* in interlocked condition be-

tween the upper end of the notch b' and the shoulder b^2 . Ventilating openings b^4 may be formed in the body of the card b , as shown in Fig. 6. When assembled, the strips a extend parallel with each other and the cards b extend parallel with each other and at right angles to the strips a , with the web portion a^3 received and held in the notches b' . In the completed carton filler the strips may be regarded as longitudinal walls or partitions 10 and the cards as cross walls.

In the embodiment of the invention illustrated in the drawings, the machine is intended for the manufacture of egg carton filler constructed as above described, although by slight variations and adjustments it may be altered to manufacture articles having intersecting walls of slightly different form. The machine illustrated embodies die press or punching mechanism at its receiving end arranged to punch notches and slots in the filler material, which, if desired, may come from two rolls of filler material.

Beyond the punching mechanism is slitting or cutting mechanism which severs one of the long sheets of material into the required number of notched strips to form the longitudinal walls of the carton filler, which strips are intermittently fed by suitable feed mechanism into the lower member of an assembling mechanism preparatory to being assembled with cards severed from the other long sheet of filler material. Feed mechanism is provided for this other sheet of filler material, which feed mechanism feeds said sheet to a co-acting upper member of the assembling mechanism that contains severing means for severing the sheet transversely into the required number of cards to make up the cross walls of the finished articles, and said upper assembling mechanism is provided with gripper heads that grip the severed cards and turn them edgewise in parallel relation to each other extending at right angles to the strips, after which the upper member of the assembling mechanism raises the gripper heads and carries them, together with the notched cards gripped therein, across the notched strips and thereafter moves the cards down over the strips and into interlocking engagement therewith, after which the assembled portions of the strips are severed from the remainder of the strips and the upper member of the assembling mechanism is moved back to its initial position, during which time the completed egg carton filler, or other assembled article, is discharged therefrom and carried away by a conveyor.

Referring now to the accompanying drawings, which illustrate the preferred embodiment of the invention, and first to Figs. 1 and 2, the reference character C designates die press or punching mechanism of conventional form which is located at the receiving

end of the machine. The die press mechanism has a suitable bed plate 25 upon which are mounted two stationary dies 26 and 27 above which are the movable dies or punches 28 and 29 that co-operate with openings in the stationary dies 26 and 27 to punch out notches and slots of the required configuration in two long sheets or strips of cardboard or other filler material A and B which may come from rolls of material (not shown) supported adjacent the machine.

The movable dies or punches 28 and 29 are carried by heads 30 and 31 guided upon suitable guide members of the press mechanism and connected to the main drive or crank shaft 32 thereof by one or more connecting rods 33. The main drive and crank shaft 32 of the press mechanism is journaled in standards 34 which comprise elements of the press frame, and said main shaft 32 is driven from any suitable source of power applied to a wheel 35 mounted on the shaft 32. The dies 28 are shaped to punch out notches and slots in the filler material A of the configurations seen in Fig. 1, and the dies or punches 29 are shaped to punch out slots in the filler material B of the configuration, also seen in Fig. 1. During the slitting or cutting operation of the filler material, the notches and slots shown in the filler material A and B subsequently become the notches a , a' and b' of the form illustrated in Figs. 5 and 6, as will appear hereinafter.

Secured to the die press C, and extending from the lower dies 26 and 27 thereof, is a table 36 over which the punched filler material is fed towards the slitting and assembling mechanism. Mounted on said table 36 adjacent the punching dies is strip slitting mechanism D for the filler material A, a simple form of which comprises disk-like knives 37 mounted upon a shaft 38 extending transversely of the machine and carried by adjustable supporting means, such as links 39 and 40, depending from a knife supporting frame 41 mounted upon the table 36 (see Fig. 2). The knives 37 are adjustable towards and away from the table 36, as, for instance, by means of adjustment screws 42 mounted in a hanger plate 43 carried by the knife supporting frame 41.

Below the knives 37 is a roller 44 journaled upon a shaft 45 supported upon the underside of the table 36, and said roller 44 projects up through a slot in the table and engages with the underside of the filler material A. The knives cut through the filler material as the latter is fed forward through the machine, thereby slitting the filler material into the required number of strips to form the longitudinal walls of the completed carton filler or other article constructed by the machine. In a machine for constructing an egg case filler having four longitudinal walls, as shown, three knives 37 may be em- 125

ployed, and said knives are spaced equidistant and located so as to slit or sever the filler material along the rows of slots seen in Fig. 1, thereby forming notched strips A' having the opposing notches a' and a² in their opposite edges, as seen in Fig. 5. An edge trimming knife 37 may also be employed.

Beyond the strip slitting mechanism D is the feed mechanism designated by E and E' (see also Figs. 3, 8 and 9) which operates to intermittently feed the two long sheets of filler material through the machine. A feed block or head 46 is provided for the strips A', which device is mounted to reciprocate longitudinally upon the table 36, and said feed block is formed with slots 47 through which extend the notched strips A'. Said slots 47 incline slightly from the vertical, as seen in Fig. 9, and are arranged in pairs, those of each pair inclining towards each other. By this arrangement of the slots in the feed block 46, the slotted strips A' are turned from a horizontal plane into inclined planes preparatory to being further turned into parallel upright planes during the assembling operation.

Spring pressed feed dogs 48 are mounted in the feed block 46, which dogs are provided with teeth that enter notches in the notched strips A' when the feed block is moved forward, thereby advancing the notched strips, together with the remainder of the filler material A the required distance to provide strips having the required length of the carton filler. The feed block 46^a (see Fig. 8) for the filler material B is also mounted upon the table 36 for lengthwise movement thereon, and said feed block overlies the filler material B and is provided with spring pressed dogs 48^a that have teeth upon their ends which enter notches of the filler material B when said feed blocks are moved forward, thereby advancing the filler material B the required distance. Spring compressed detents or dogs 129^a and 129^b (see Figs. 1^a, 21 and 33) located adjacent the assembling mechanism and engaging in the slots of the filler material prevent retrograde movement of the filler material.

Mechanism is provided for reciprocating the feed blocks 46 and 46^a in timed relation to the other operating parts of the machine, and, as shown, said mechanism comprises rocker arms 49 and 49^a (see Fig. 3) connected to the feed blocks 46 and 46^a by links 50 and 50^a. The rocker arms 49 and 49^a are fulcrumed upon the framework G of the machine and are connected to operating struts 51 and 51^a that co-operate with a cam block 52 mounted upon a cam shaft 53 to oscillate the rocker arms and thereby reciprocate the feed blocks 46 and 46^a. The cam block 52 is formed with a suitably shaped cam groove 54 in which travels a pin or roller 55 carried

by the operating struts 51 and 51^a. The shaft 53 is journaled in suitable bearings carried by the framework G.

When the length of material necessary to form the longitudinal walls of a carton filler or the like is less than that required to form the cross walls of the filler, the feed block actuating mechanism is arranged to impart a longer stroke to the feed block 46^a than the feed block 46, and this has been accomplished in the machine illustrated by making the throw of the arm 49^a greater than that of the arm 49. The cam is timed to feed the filler material forward during the intervals of inactivity of the punching mechanism and assembling mechanism.

The cam shaft 53 receives its motion from the main drive shaft 32 of the machine through power transmitting mechanism which may comprise an upright shaft 56 journaled in bearings carried by a framework of the machine and geared to the shaft 53 by intermeshing beveled pinions 57 and 58 on the ends of said shafts 53 and 56. On the upper end of the shaft 56 is a beveled pinion 59 which meshes with a beveled pinion 60 fast on the end of the cam shaft 61 journaled in bearing brackets carried by the framework of the machine.

Upon one end of the cam shaft 61 is a gear 62 which meshes with a gear wheel 63 fast upon a cam shaft 64 journaled in bearing brackets carried by the frame of the machine. A sprocket chain 65 trained over a sprocket wheel 66 (see Fig. 1) on the crank shaft 32 and a sprocket wheel 67 on the cam shaft 64 provides means for transmitting motion from the crank shaft 32 to the cam shaft 64. From the cam shaft 64 power is transmitted to the cam shaft 53 by the gearing described. Obviously, other equivalent power transmitting gearing may be substituted for the one shown for transmitting power from the crank shaft 32 to the several cam shafts 53, 61 and 64. Beyond the feed mechanism is the assembling mechanism, indicated generally at F, in one part of which the filler material B is cut transversely to form the cards b that comprise the cross walls of the egg carton filler or other filler. The cards are thereafter assembled in another part of the assembling mechanism with the strips that comprise the longitudinal walls, thereby completing the article.

Referring now to Figs. 10 to 20, inclusive, at the end of the table 36 is a bed plate 68 which extends lengthwise of the machine with its upper face flush with the upper face of the table 36. The bed plate 68 is mounted upon a table or platform 69 supported upon the framework of the machine. Mounted in said bed plate, and movable lengthwise of the machine, are pairs of U-shaped gripper head guides 70, those of each pair being dis-

- posed opposite to each other and having feet 71 contained in slideways 72 formed in the upper face of the bed plate 68. The feet are retained in said slideways by plates or bars 73 and 74 secured to the bed plate and overhanging the slideways 72. There are as many pairs of U-shaped gripper head guides 70 as there are cards employed in the article to be manufactured, and in the operation of the machine, the filler material B is fed through the space between the opposing gripper head guides 70 where it is severed transversely into the individual cards required for a complete article, and thereafter the cards are gripped by the gripper heads, as will be presently described, and lifted and turned into vertical planes parallel with each other. The gripper heads are seen at 75 and comprise separable gripping jaws 76 and 77 that are rotatably mounted in the downwardly projecting arms 78 of U-shaped gripper head carriers 78 which are slidably carried by a supporting bar 79 which is adapted to be reciprocated transversely of the machine in transferring the cards to the lower member of the assembling mechanism. The supporting bar 79 is carried by an operating lever 80 which is oscillated transversely of the machine and also raised and lowered in the operation of transferring the cards from one station to another, as will be fully described hereinafter.
- A swivel connection 81 is provided between the operating lever 80 and the supporting bar 79 (see Fig. 4) to permit of the angular movements between the operating lever and supporting bar, and a horizontally extending stationary guide bar 82 (see Figs. 1^a and 4) is provided above the end of the operating lever 80, which guide bar is formed with a groove or guideway 83 in its lower side in which travels a pin or roller 84 carried upon the upper end of the swivel connection 81 between the operating lever 80 and supporting bar 79. The guide bar 82 extends transversely across the machine and is supported from the framework thereof. Said guide bar 82 operates to guide the card transferring mechanism to move in a straight line during its reciprocating movements from one side of the machine to the other.
- During the interval of time that the filler material B is fed into the gripper heads of the assembling mechanism, the gripper head carriers 78 and therewith the gripper heads 75 are held stationary with the jaws of the gripper heads separated and occupying a position wherein the filler material may be fed through the spaces between the jaws. This position is clearly illustrated in Fig. 11. In the upper face of the bed plate 68 are grooves 85 spaced equi-distant and arranged to receive the jaws 77 of the gripper head with their upper sides flush with the top of the bed plate 68.
- Along one side of the jaws 76 are secured knives 86 that co-operate with the flat sides of the other jaws 77 to cut or shear the filler material B into the individual cards b after the filler material has been fed into position between the jaws of the gripper heads, and mechanism is provided, as will be hereinafter described, for bringing the jaws 76 and 77 together, thereby severing the filler material into individual cards and gripping the cards 75 between them. The upper face of the bed plate is notched, as shown, to permit the knives 86 to pass the sides of the jaws 77 during the cutting or shearing operation. Means are provided for locking the jaws together 80 after the card have been gripped, thereby holding the jaws in locked position until the carton filler has been completely assembled and is ready to be discharged from the machine. 85
- The jaw 76 of each of the gripper heads is formed of two sections secured together, one of which is chambered to receive locking dogs 87, the ends 88 of which are arranged to enter notches 89 formed in one of the sections 90 of the jaw 76 (see Figs. 17 and 18). The locking dogs 87 are slidably mounted in recesses formed in the ends of the jaw 77 and move bodily with such jaw, but are capable of being moved endwise of themselves to effect a 95 locking engagement between the two jaws.
- The jaws are spring pressed away from each other by coiled compression springs 89^x interposed between one of the sections of the jaws and the locking dog 87, as is clearly indicated in Fig. 17. The jaws of each gripper head are brought together by arresting the downward movement of the jaw 77 and continuing the downward movement of the jaw 76, and, as shown, the jaws 77 are provided with downwardly projecting pins 90 that enter sockets contained in the upper face of the bed plate 68, and steady the lower jaw 77 during the closing movement of the jaws. Downward movement of the jaws 76 from the position seen in Fig. 11, caused by a final downward movement of the operating lever 80 and gripper head carriers 78, effects the closing action of the jaws. 100 110
- Means are provided for moving the locking dogs 87 into locking engagement with the jaw 76 of the gripper head, and, as shown, said means comprises notched reciprocatory lock actuating bars 91 (see Fig. 29) contained in grooves in the bed plate 68, which bars have inclined faces that extend into notches 92 formed in the lower side of the locking dogs 87. The locking bars 91 are reciprocated by levers 91^a and cam actuating mechanism immediately upon closing the 120 jaws on the cards B. The levers 91^a extend down below the table or platform 69 and each has a roller on its lower end co-operating with a cam 91^b mounted on a cam shaft 136. The cams 91^b are timed to reciprocate 130

the notched bars 91 and thereby move the locking dogs 87 into engagement with the jaws 76 when the jaws 76 and 77 have been closed upon the cards. In the operation of 5 the machine, the jaws remain closed until the egg case filler has been assembled and is ready to be discharged, whereupon the jaws are opened by fingers 93 (see Figs. 10, 21 and 32) on the guide bars 116 for the grip- 10 per heads and having inclined faces which engage in the grooves 92 of the locking dogs and retract them, thereby permitting the springs 89^x to open the jaws and release the completed egg case filler therefrom.

15 In addition to the springs 89^x for opening the jaws 76 and 77, positive means have been provided which may comprise spring pressed pins 89^a (see Fig. 18) seated in recesses formed in the stationary jaws 76 and 20 having inner ends adapted to be projected against the movable jaws 77 and other ends 89^b protruding from the opposite faces of the stationary jaws and arranged to be engaged by cam blocks 89^c which are provided 25 upon the guide bars 116 (see Figs. 21 and 32). The guide bars extend from the gripper head guides and over the lower member of the assembling mechanism and guide the gripper heads during their movement to and 30 from the lower member of the assembling mechanism. The fingers 93 and cam blocks 89^c are positioned below the paths of movement of the locking dogs 87 and jaw opening pins 89 during the movement of the gripper heads toward the lower member of the assembling mechanism, but on the return movement of the gripper heads, the latter are depressed as they pass said fingers and cam blocks to thereby effect the opening of 35 the jaws.

40 As has been explained, the gripper heads are rotatably mounted in the downwardly projecting arms 78^a of the gripper head carriers 78, and, for this purpose, the gripper heads are provided with trunnions 94 upon their ends that enter bearing apertures in said downwardly projecting arms. Adjacent their ends, the gripper heads are formed with gear segments 95 which are adapted to 45 mesh with rack teeth 96 formed in one edge of the upright bar 70^a of the gripper head guides 70 during the upward movement of the gripper heads past said rack teeth, whereby said gripper heads are partially rotated.

50 The gripper heads are also formed with flat faces 97 and 98 adjacent the gear segments, which straight faces are arranged to travel along the adjacent straight sides of the up- 55 right bars 70^a and thereby hold the gripper heads from rotating except when the gear segments 95 encounter the rack teeth 96 during which interval the gripper heads are rotated through an arc of ninety degrees, bringing the cards gripped thereby into up- 60 right position, as seen in Figs. 10 and 14,

which is the position occupied by the cards when being assembled with the strips.

When forming a carton filler or other article in which the cross walls are of greater height than the distance between them, and in which the cross walls are cut from a long sheet or length of filler material, as in the present case, it is necessary to adjust the cards *b*, while held in the gripper heads, into positions corresponding with the distances between the notches of the strips *a*, and this is accomplished by justifying mechanism, which will now be described.

70 The end gripper head guides 70 of the series are provided with downwardly extending lugs 99, to the forward lugs of which is connected a lever 100 (see also Fig. 4) fulcrumed upon the framework of the machine and operated by a cam 101 and a link or strut 102 having a roller 103 running in the cam groove 104 of the cam. The cam groove is designed to oscillate the lever 100 in timed relation to the other movements of the gripper heads. The end gripper head guides 70, during the justifying action, are 80 moved towards each other sufficiently to bring the endmost cards, carried by the gripper heads thereof, to a spaced relation identical with the distance between the endmost notches of the strips *a*, whereby when the end 85 cards are brought down across said strips, they will enter the endmost notches thereof.

85 For producing this relative movement between the pairs of gripper head guides, rack bars 105 and 106 are connected to the end 90 gripper head guides, which rack bars mesh respectively with two intermeshing gear wheels 107 and 108. In the operation of the machine, the reciprocating movements of the rack bars 105 imparted to it by the lever 100 95 are transmitted to the rack bars 106 through the instrumentality of the intermeshing gear wheels 107 and 108 and the endmost gripper head guides are thereby moved toward and 100 away from each other.

105 For equalizing the distance between all of the gripper heads, the endmost gripper head guides are provided with means for moving the intermediate gripper head guides (with the exception of the middle one which is made stationary), and said means, as shown, 110 comprises drag links 109 (see Fig. 16) each connected to an endmost gripper head guide as by a lug 110 entering a notch in the side of the end gripper head guides. The drag links slide in the grooves 72 of the bed plate 68 and have other lugs 111 and 112 thereon that enter elongated notches 113 and 114 in the other gripper head guides (see Fig. 1^a). The notches in the gripper head guides and lugs of the drag links provide lost motion connections between the intermediate gripper head guides and the endmost ones enabling the endmost gripper head guides 115 to move the intermediate ones the required 120

125 65 right position, as seen in Figs. 10 and 14,

distance to space all of the gripper head guides equidistantly, the spacing being the same as the spacing of the notches in the strips *a*. The lugs 111 and 112 engage with the ends of the slots in the intermediate gripper head guides, the lug 111 first engaging the end of the slot in which it travels and the lug 112 thereafter engaging the end of its slot, thereby moving the gripper head guides through the proper respective distances to bring the gripper heads into spaced relation with the cards *b* spaced the same distance apart as the notches in the strips *a*.

If desired, drag links 109^a (see Fig. 11), similar to the drag links 109, may be provided between the gripper head carriers 78 and bar 79 for effecting the justifying action between the gripper head carriers 78. The drag links 109^a are slidably contained in grooves formed 20 in the bar 79 and have lugs, as in the case of the drag links 109, entering notches in the gripper head carriers 78. Additional justifying means may be provided for the gripper head carriers 78, as shown in Fig. 30. The 25 endmost gripper head carriers may be provided with pins or rollers 78^x adapted to travel in inclined grooves or guideways 78^y formed in standards 78^z supported on the framework of the machine. The grooves 78^y 30 are located so as to encounter the pins or rollers 78^x at the instant that the lever 100 actuates the end gripper heads, as above explained, thereby aiding the primary justifying mechanism in adjusting the gripper head 35 guides and gripper head carriers.

After the cards *b* have been gripped in the gripper heads 76, and the latter raised and rotated to bring the cards into upright position, the gripper heads are moved across the machine to the lower member of the assembling mechanism and depressed to thereby assemble the cards with the strips to complete the carton filler. The operating lever 40 80 is actuated by certain cams, as will be 45 hereinafter set forth, to move the gripper head carriers and therewith the gripper heads from one position to the other.

Adjacent the gripper head guides is a vertically slotted bar 115 (see Fig. 10) which 50 extends lengthwise of the machine and is secured to the member 74. To the upper end of said slotted bar 115 are secured the guide rails 116 which extend horizontally across the lower member of the assembling mechanism (see Figs. 1^a and 27) and are supported 55 at their outer ends by uprights or other supports 116^a that extend up from the table or platform 69. One of the side faces of each of the guide bars 116 is flush with a face of 60 an upright member 70^a of each gripper head guide (see Fig. 14), thereby forming a track which is a continuation of said face of each gripper head guide, and when the gripper heads are moved across the machine to trans- 65 fer the cards *b* from the place where they are

cut to the lower member of the assembling mechanism, the flat faces of the gripper heads travel along the flat faces of the bars 116 whereby the gripper heads are held against turning upon their axes. It will be understood that when the operating lever 80 is moved across the machine from the position seen in Fig. 1^a, that the upright members 78^a of the gripper head carriers 78 are moved through the spaces between the upright members of the gripper head guides, thereby bringing the gripper heads into positions above the lower member of the assembling mechanism, after which the gripper head carriers and therewith the gripper heads are depressed to bring the cards *b* into locking engagement with the strips *a*.

The lower member of the assembling mechanism will now be described. This lower member contains a number of vertically slotted guide blocks 117 and 117^a (see Figs. 21 to 26) arranged in rows, four rows being shown, and the slots of said blocks form channels for receiving the end portions of the strips A'. Except during the interval that the members of a carton filler or other article are being assembled, the slotted guide blocks 117 and 117^a are inclined slightly, as seen in Figs. 23 and 27, but during the assembling 90 of the article, the guide blocks are moved into the upright position, seen in Fig. 24, the purpose of which will be hereinafter explained.

The guide blocks are formed with downwardly projecting tail pieces 118 which are 100 rockingly mounted in slides 119 and 119^a that are capable of movement transversely, of the machine and are slidably guided in the slots of a slotted guide member 120, which is preferably formed as a part of the table or platform 69. The tail pieces 118 are formed with trunnions or short shafts 121 that are journaled in bearings formed in the slides 119 and 119^a to permit the rocking movement of the guide blocks 117 and 117^a. 105 An operating strut 122 is interposed between the two tail pieces 118 in each slide and a coiled compression spring 123 is provided in a groove in the slotted guide member 120 between one of the tail pieces and an end of said groove. The purpose of this arrangement is to impart synchronous parallel movement to the two guide blocks 117 and 117^a 110 operated by each slide 119 and 119^a.

The means for moving the guides 119 and 119^a in the direction to straighten up the 115 guide blocks 117 and 117^a comprises cam faces 124 formed upon the arms 78^a of the gripper head carriers 78, which cam faces engage with upstanding lugs 125 and 125^a 120 formed on the slides 119 and 119^a. The cam faces 124 are arranged to engage with the lugs 125 and 125^a while the cards *b* are being inserted into the slots of the strips *a*. The parts 78^a (see Figs. 10 and 16) of the 125 130

gripper head carrier arms 78^a, on which the cam faces 124 are formed, may have a limited amount of movement relative to the main parts of said arms 78^a in a lengthwise direction to permit the straight faces of the parts 78^c to hold the guide blocks 117 and 117^a in upright position for a slight interval of time while the gripper heads are being raised to carry away the completed filler. The purpose of this is to insure the interlocking engagement between the webs *a*³ of the cards with the shoulders *b*² of the strips. The guide blocks being held upright for some time during the removal of the completed filler from them, the strips are permitted to remain upright after having been assembled, and, consequently, remain interlocked with the cards.

The sliding connection between the parts 78^c and the remainder of the arms 78^a may be provided by forming a lap joint between the two parts of each arm and connecting them by a screw 78^d threaded in one part and entering a slot in the other. Guide bars 126 are placed behind the upright lugs 125 and 125^a, and the ends of the arms 78^c containing the cam faces 124 pass down between said guide bars 126 and the upstanding lugs 125 and 125^a. When the arms 78^a are raised out of contact with the lugs 125 and 125^a, the coiled compression springs 123, which have been compressed by the movement of the slides 119 and 119^a expand, thereby returning the slides to the normal position shown in Fig. 23 and again tilting the guide blocks.

Between the pairs of guide blocks 117 and 117^a are upstanding lugs 127 which are supported from the slotted guide member 120 of the table 69, and said lugs 127 form stops or abutments for the upper ends of the guide blocks 117 and 117^a, whereby when the slides 119 and 119^a are moved by the cam faces 124 to straighten up the guide blocks, the upper ends of the latter will encounter the stops or abutments 127 after which the continued movement of the slides acts to move the guide blocks from the inclined position, seen in Fig. 23, to the upright position seen in Fig. 24.

The slotted blocks 117 and 117^a hold the upper edges of the notched strips in position to enter the tapering inlets to the slots *b*' of the cards *b*, (see Fig. 27) and as the cards are moved down across the strips, the inclined strips enter the notches *b*' through said tapering ends of the notches, thereby freely passing by the shouldered portions *b*² and entering the main parts of the notches. Because of the inclined position of the strips, there is no danger of bending or distorting the shouldered parts *b*² of the notches *b*'. However, as the cards are moved downward, the cam faces 124 of the arms 78^a move the slides inward, thereby straightening up the guide blocks 117 and 117^a and bringing the strips 65 into upright position with the web portions

*a*³ thereof contained in the notches *b*' between the upper ends of the notches and the shouldered portions *b*², in which position the cards and strips are interlocked.

While the cards are being assembled with the strips, the portions *a* of the strips A' that form the filler are severed from the remainder of the strips by knives 128 and 128^a which are mounted in guide blocks 129 for reciprocal movement therein in a vertical direction. Between the guide blocks 129 are slots or channels 130 through which the notched strips A' are fed to the slotted guide blocks 117 and 117^a, and said knives 128 and 128^a co-operate with the front edges of said blocks to shear the portions *a* of the strips forming the egg case filler from the remainder A' of the strips.

From the knives 128 and 128^a extend shanks 131 which are connected by a cross connection 132 with an operating lever 133 (see Figs. 4 and 22) fulcrumed upon the framework of the machine and co-operating with a cam block 134 to reciprocate the knives 128 and 128^a at the proper time to sever the assembled portions *a* of the strips from the remainder thereof. Tension springs 135 (see Fig. 4) secured to the cross connection 132 and to some stationary portion of the framework serve to hold the knives in close contact with the co-operating shearing edges. The cams 91^b, 101 and 134 are mounted upon the cam shaft 136 which is journaled in bearings carried by the framework of the machine, and said shaft may receive its motion from the cam shaft 53 through a shaft 137 having bevelled pinions 138 and 139 (see Figs. 3 and 4) that mesh respectively with pinions 140 and 141 on the cam shafts 53 and 136. In the blocks 129 are the spring pressed dogs 129^a which engage in notches in the strips A' and prevent accidental retrograde movement of said strips.

The mechanism for actuating the card transferring mechanism comprises the operating lever 80, as above explained, a cam 142 mounted on the cam shaft 61 and cams 143 and 144 mounted on the cam shaft 64. The operating lever 80 is pivotally mounted for oscillation in a horizontal plane and in vertical planes, the pivotal connection being shown in Figs. 1 and 2, where it will be seen that the lever is connected by means of a link 145 to a forked member 146 swiveled in an arm 147 of a bracket 148 supported by the uprights 34 of the press mechanism.

The cam 142 is formed with a circumferential cam groove 149 in which travels a roller 150 that is carried by the operating lever 80, and said cam groove is shaped to effect the oscillations of the operating lever 80 through a horizontal plane from the position occupied in Fig. 1^a to a position over the lower member of the assembling mechanism. The shape of the cam groove is designed to permit the operating lever to remain at the end of its 130

stroke during the interval that the filler material B is severed into cards and while the gripper heads are being raised into position for transversing them to the lower member 5 of the assembling mechanism. The cam groove 149 is also arranged to permit the operating lever to remain at the other end of its stroke while it is raised and lowered during the assembling of the cards with the strips.

The cams 143 and 144 are located on each side of the operating lever 80, as seen in Fig. 1^a, and operate to raise and lower the operating lever at the ends of its stroke through 15 the horizontal plane. The cam 143 is formed with a cam groove 151 in its side in which a roller 152 is adapted to travel, and which is carried upon one side of the operating lever 80 and the cam 144 is formed with a cam 20 groove 153 in its side in which a roller 154 carried on the other side of the operating lever is adapted to travel. When the lever is in the position occupied in Fig. 1^a, the roller 152 is being acted upon by the cam groove 151 25 of the cam 143, and, as a consequence, the lever is being lowered and raised to thereby move the gripper head carriers and therewith the gripper heads to a position where the open jaws receive the filler material and afterwards raise it to the position from which the 30 gripper head carriers and gripper heads are transferred to the other side of the machine.

The cam 143 has a concentric portion 155 (see Fig. 3) through which the roller 152 travels while the gripper heads are depressed and the filler material is being fed through them, and said cam block 143 has a sharply curved part 156 which encounters the roller 152 immediately before the concentric part 40 of the groove reaches the roller, and said sharply curved part 156 of the cam groove acts to further depress the operating lever, thereby moving downward the gripper head carriers 78 and therewith the jaws 76 of the 45 gripper heads, thus bringing the knives 86 down and cutting the filler material into the individual cards which are then gripped between the jaws 76 and 77. The eccentric part 50 of the cam then acts to raise the operating lever and parts carried thereby.

The cam groove 149 of the cam 142 is so timed that when the operating lever 80 and parts carried thereby have been fully raised, the cam 142 then moves the operating lever 55 horizontally across the machine to the lower member of the assembling mechanism during which time the roller 152 is withdrawn from the cam groove 151 of the cam 143 and the roller 154 is entered into the cam groove 60 153 of the cam 144, whereby the operating lever and parts carried thereby are again depressed to effect the assembling of the cards with the strips. A support 157 is provided for supporting the operating lever during 65 its oscillating movements across the ma-

chine, and said support is carried by a bracket 158 mounted upon the framework of the machine. The support 157 is cushioned whereby it may yield downwardly slightly, and, as here shown, a coiled compression 70 spring 159 is provided between the support and the socket through which the stem 160 of the support extends. In moving from one side of the machine to the other, the operating lever rides upon the support 157, but is free 75 to oscillate vertically at the limits of its horizontal strokes. On the cam shaft 64 is a cam 161, the nose of which is arranged to strike against the upper side of the operating lever 80 while it is being returned from the assembling position to thereby depress the operating lever slightly and thereby unlock and open the jaws of the gripper heads to release the completed carton filler from the 80 gripper heads.

A conveyor, shown in the form of a belt 162, is provided, which travels between the two lower members of the assembling mechanism and is trained around pulleys 163 and 164, the pulley 164 being mounted upon a shaft 90 165, on which is a belt pulley 166 over which is trained a belt 167 which runs over a belt pulley 168 fast on the shaft 136. After the carton fillers have been completely assembled, they are dropped upon the conveyor 162 as 95 the operating lever passes over the same, and said conveyor discharges the completed carton fillers from the machine.

In the operation of the machine, two sheets of cardboard or other carton filler material 100 of indefinite length are fed into the machine at the receiving end thereof where the die press mechanism punches out the notches and slots, seen in Fig. 1. During the punching operation the material is at rest, and immediately after the punching operation the feeding devices feed a length of both notched sheets into the assembling mechanism, the punched sheet A passing the severing mechanism D and being severed into the individual 105 notched strips A' which enter the channels of the slotted blocks 117 and 117^a where said notched strips stand in slightly inclined planes.

The sheet B is fed through the open gripper 115 jaws 76 and 77, and at this point in the operation of the machine, the sharp curve 156 of the cam 143 encounters the roller 152 of the operating lever 80 and moves the lever downwardly, thereby moving the supporting bar 120 79 downward and therewith the gripper head carriers 78 and gripper heads, which gripper head carriers and gripper heads at this time occupy positions between the upright members of the gripper head guides with the lower jaws 77 of the gripper heads resting in the grooves 85 of the bed plate 68. This final downward movement of the operating lever brings the knives 86 down upon the sheet, thereby severing the same into individual 125 130

cards and also closes the gripper jaws 76 and 77 upon the individual cards.

Thereupon, the eccentric part of the cam 143 raises the operating lever 80 and parts carried thereby, and as the gear segments 95 of the gripper heads pass the rack teeth 96 on the gripper head guides, the gripper heads and therewith the cards gripped thereby are turned from the position seen in Fig. 12 to that seen in Fig. 13 where they occupy vertical positions parallel with each other and extend transversely of the strips now held in the lower member of the assembling mechanism. As the gripper heads move upwards, the cam 101 actuates the lever 100 thereby adjusting the gripper head guides to bring the cards into properly spaced relation to enter the notches of the strips. As the lever continues to swing in an upward direction, the gripper heads are raised to the level of the guide bars 116 at which time the cam 142 swings the operating lever 80 across the machine through a horizontal plane during which time the lever rides upon the support 157 and the gripper head carriers, gripper heads and the cards carried thereby are transferred to the other side of the machine in position above the lower member of the assembling mechanism, whereupon the roller 154 of the operating lever enters the cam groove of the cam 144, and, as a consequence, the lever 80 is depressed, thereby bringing the notches b' of the cards b through the notches a' of the strip a and across the webs a^3 thereof.

Since the strips are held in their inclined position they freely enter the tapering ends of the notches b' and pass by the shouldered portions b^2 without bending or distorting them, and as the cards continue their downward movement, the cam faces 124 of the gripper head carriers 78 encounter the lugs 125 and 125^a of the slides 119 and 119^a, thereby moving said slides and straightening up the slotted blocks 117 and 117^a and permitting the webs a^3 of the strips a to pass the shoulders b^2 whereupon the cards and strips become interlocked.

At this point in the operation of the machine, the knives 128 and 128^a are drawn downward, thereby shearing the assembled parts of the strips from the remainder and the cam 144 raises the operating lever and therewith the gripper heads which carry with them the completed carton filler. The operating lever is raised until the gripper heads are again brought on the same level with the guide bars 116, whereupon the cam 142 moves the lever back towards its initial position, but when the lever reaches a position where the completed carton filler is suspended over the conveyor 162, the nose of the cam 161 encounters the operating lever 80 and depresses it slightly, thereby depressing the gripper heads and thereby moving

the notches 92 of the locking dogs into engagement with the fingers 93, the inclined faces of which engage the locking dogs and retract them from their locked position whereby the springs 89^c act to open the jaws. Sufficient space is provided between the ends of the fingers 93 and bottoms of the notches to permit the jaws to open. The cam blocks 89^c encounter the protruding ends of the pins 89 and the cam faces of the cam blocks force the pins inward against the movable jaws or interposed cards, thereby positively separating the jaws and permitting the carton filler to fall upon the conveyor by which it is discharged from the machine. After the nose of the cam 161 passes the operating lever, the spring 159 lifts the operating lever into its normal horizontal plane and the cam 142 continues to move the operating lever 80 to the end of its horizontal stroke at which time the roller 152 thereof enters the cam groove in the cam 143 and the lever and parts carried thereby are depressed to the initial or starting position above mentioned. This cycle of operation is carried on indefinitely and at a relatively high rate of speed.

I claim:

1. In a machine of the class described, the combination with mechanism for forming two sets of notched pieces, the pieces of one set extending transversely of the pieces of the other and adapted to interlock therewith, of one member of an assembling mechanism having parallel slotted guide members for receiving the notched pieces of one set, a co-acting assembling member having parallel gripper heads adapted to grip and turn the notched pieces of the other set into parallel relation, and actuating mechanism for moving one member of said assembling mechanism and therewith the notched pieces of one set across and down upon the notched pieces of the other set with the notches of one set intersecting the notches of the other set.

2. In a machine of the class described, the combination of punching mechanism, slitting means for one sheet, feed mechanism for the material, an assembling member into which notched pieces cut from one sheet are fed in parallel relation to each other, mechanism for cutting the other sheet transversely to form individual pieces, assembling mechanism including gripper heads adapted to grip the notched pieces cut from the second mentioned sheet, and mechanism for moving said gripper heads over the assembling member in transverse relation to the notched pieces held therein, and thereafter bringing said pieces together in interlocked relation.

3. In a machine of the class described, the combination of punching mechanism acting on two sheets of material, strip cutting mechanism for cutting one of the sheets into notched strips and card cutting mechanism

for cutting the other sheet into notched cards of less length than the strips, assembling mechanism for assembling the notched cards with the notched strips in interlocked relation, and independent feed mechanism for each of the sheets, each feed mechanism including a reciprocating sheet propelling member, and one of the feed mechanisms having a greater length of stroke than the other, 10 and one sheet propelling member having individual gripping means for each notched strip.

4. In a machine of the class described, the combination of notched strip forming means 15 and notched card forming means, feed mechanism for the material, a lower member of an assembling mechanism in which the notched strips are fed, vertically movable gripper heads for gripping the notched cards, means 20 for partially rotating said gripper heads to bring the cards gripped thereby into parallel relation, and means for moving said gripper heads over the lower member of the assembling mechanism and depressing said gripper 25 heads to bring the notched cards gripped thereby into interlocked relation with the notched strips.

5. In a machine of the class described, the combination of notched strip forming means 30 and notched card forming means, feed mechanism for the material, a lower member of an assembling mechanism in which the notched strips are fed, vertically movable gripper heads for gripping the notched cards, means 35 for partially rotating the gripper heads to bring the cards gripped thereby into parallel relation, means for moving said gripper heads over the lower member of the assembling mechanism and depressing said gripper heads 40 to bring the notched cards gripped thereby into interlocked relation with the notched strips, and strip severing mechanism for severing the assembled strip from the remainder.

6. In a machine of the class described, the combination with material feeding mechanism, notched strip and notched card forming mechanism, of a lower member of an assembling mechanism into which the notched strips are fed, gripper heads adapted to grip 45 the notched cards, means for partially rotating said gripper heads to bring the notched cards into parallel relation extending transversely of the notched strips, and transfer mechanism for moving said gripper heads 50 over the lower member of the assembling mechanism and depressing the gripper heads to bring the notched cards and notched strips 55 into interlocked relation.

7. In a machine of the class described, the combination of punching mechanism for a sheet of material, feed mechanism for said sheet of material, rotatably mounted card gripping heads having operable and closable jaws, and means for partially rotating said 60 card gripping heads whereby cards gripped

thereby are moved into parallel relation with each other.

8. In a machine of the class described, the combination of a gripper head guide, a vertically reciprocable gripper head carrier, a gripper head rotatably mounted in said gripper head carrier, and co-acting means on said gripper head guide and gripper head for partially rotating the gripper head. 70

9. In a machine of the class described, the combination of a series of gripper head guides, vertically reciprocable gripper head carriers, gripper heads rotatably mounted in said gripper head carriers and arranged to grip notched cards, and co-acting means between said gripper head guides and gripper heads for partially rotating said gripper heads to move said cards into parallel relation. 75

10. In a machine of the class described, the combination of a series of gripper head guides, a series of vertically reciprocable gripper head carriers, a series of gripper heads rotatably mounted in said carriers and having jaws arranged to grip notched cards, and coacting means on said gripper head guides and gripper heads for partially rotating the gripper heads to move the cards into parallel relation with each other. 80

11. In a machine of the class described, the combination of a bed plate over which a sheet of filler material is fed, a series of gripper head guides projecting up from said bed plate, a series of vertically reciprocable gripper head carriers, a series of gripper heads rotatably mounted in said gripper head carriers and having jaws through which the material is fed, knives carried by one jaw of each gripper head adapted to sever said material into individual cards, and coacting means between the gripper head guides and gripper heads for partially rotating the gripper heads to move the cards into parallel relation. 90

12. In a machine of the class described, the combination of a bed plate over which a sheet of filler material is fed, gripper head guides projecting up from said bed plate, vertically reciprocable gripper head carriers, gripper heads rotatably mounted in said gripper head carriers and having jaws, and a knife on one of the jaws of each gripper head adapted to sever the sheet into individual cards, locking means for locking the jaws in closed position upon the cards gripped thereby, and coacting means on the gripper head guides and gripper heads for partially rotating the gripper heads to bring the cards into parallel relation. 100

13. In a machine of the class described, the combination of a bed plate, a series of gripper head guides slidably mounted in said bed plate, a series of gripper head carriers movable into and out of said gripper head guides, gripper heads rotatably mounted in said 105 110 115 120 125 130

gripper head carriers, and justifying mechanism associated with said gripper head guides for adjusting the spaced relation between said gripper head guides and gripper heads.

14. In a machine of the class described, the combination of a bed plate, a series of gripper head guides slidably mounted therein, a series of vertically reciprocable gripper head carriers movable into and out of said gripper head guides, a series of gripper heads rotatably mounted in said gripper head carriers and having sheet severing mechanism for severing a sheet of material into individual cards and jaws for gripping the individual cards, co-acting means between the gripper head guides and gripper heads for partially rotating the gripper heads to bring the cards into parallel relation, and justifying mechanism associated with the gripper head guides for adjusting the spaced relation of the gripper head guides and gripper heads.

15. In a machine of the class described, the combination of a bed plate, a series of gripper head guides slidably mounted thereon, a series of vertically reciprocable gripper head carriers movable into and out of said gripper head guides, gripper heads rotatably mounted in said gripper head guides and having card gripping jaws, co-acting means between the gripper head guides and gripper heads for partially rotating the gripper heads to move the cards gripped thereby into parallel relation, drag links having lost motion connections between the gripper head guides, and mechanism for adjusting the endmost gripper head guides whereby the several gripper heads are adjusted into altered spaced parallel relation.

16. In a machine of the class described, the combination of a U-shaped gripper head guide, a gripper head carrier having downwardly projecting arms arranged to enter the space between the two members of the U-shaped gripper head guide, mechanism for reciprocating said gripper head carrier in the gripper head guide, a gripper head rotatably mounted in said gripper head carrier and having jaws adapted to grip a card, there being a gear segment on said gripper head, and co-acting rack teeth on the gripper head guide for partially rotating the gripper head when reciprocated by said gripper head carrier.

17. In a machine of the class described, the combination of one member of an assembling mechanism having parallel notched strip receiving channels, a series of rotatably mounted gripper heads extending at right angles to the channels in said member of the assembling mechanism, said gripper heads having jaws arranged to grip individual notched cards, means for partially rotating said gripper heads to bring the cards into parallel

relation, and mechanism for moving the gripping heads over said member of the assembling mechanism and depressing the gripper heads to bring the notched cards into interlocked relation with the notched strips. 70

18. In a machine of the class described, the combination of an assembling mechanism comprising a series of vertically reciprocable gripper heads having jaws for gripping notched cards, of a co-acting member of the assembling mechanism having inclined guides for the notched strips, actuating mechanism associated with the gripper heads for moving the same toward and away from the co-acting member of the assembling mechanism whereby the notched cards and strips are assembled in interlocked relation, and mechanism for straightening up said inclined guides during the assembling operation. 75 80 85

19. In a machine of the class described, a member of a carton filler assembling mechanism comprising a plurality of slotted guide blocks for receiving notched strips and arranged in rows and normally held in inclined positions, movable supporting members for said guide blocks, and means for moving said supporting members to thereby straighten up said guide blocks into substantially parallel vertical planes. 90 95

20. In a machine of the class described, the combination of a plurality of slotted guide blocks adapted to receive notched strips, said blocks being arranged in spaced rows and normally tilted out of vertical planes, and slide members in which said guide blocks are rockingly mounted, said slide members acting when moved to straighten up said guide blocks into substantially vertical planes. 100

21. In a machine of the class described, the combination of a plurality of slotted guide blocks arranged in rows, the blocks of each row being held in inclined positions, slide members in which said guide blocks are rockingly mounted, and vertically reciprocable gripper head carriers having cam faces thereon co-acting with said slide members to move the latter endwise and thereby straighten up the guide blocks into substantially vertical planes. 105 110 115

22. In a machine of the class described, the combination with gripper head carriers and gripper heads mounted therein, of an operating lever connected to and operating said gripper head carriers, a cam co-operating with said operating lever to oscillate the same through a horizontal plane, and other cams, one disposed on each side of said operating lever and arranged to oscillate said operating lever through vertical planes at both ends of its stroke. 120 125

23. In a machine of the class described, the combination with gripper head carriers, gripper heads mounted thereon, an operating lever connected to and operating said gripper 130

head carriers, mechanism for oscillating said operating lever through a horizontal plane, and through vertical planes at the ends of its horizontal strokes, and means for depressing said operating lever at a place intermediate the ends of its return strokes through the horizontal plane.

24. In a machine of the class described, the combination with gripper head carriers, gripper heads mounted thereon and having card gripping jaws, means for locking said jaws in closed position upon the cards carried thereby, a member of an assembling mechanism, mechanism for moving said gripper head carriers over said member of the assembling mechanism and bringing the cards into interlocked relation with notched strips held in said member of the assembling mechanism, and means for unlocking the jaws of the gripper heads during the return movement of the gripper heads after the cards and strips have been assembled.

25. In a machine of the class described, the combination of slotted notched card gripper heads, an assembling member having grooved guides for receiving notched strips, mechanism for reciprocating said gripper heads over the assembling member, and means for depressing the gripper heads to bring the notched cards into interlocked relation with the notched strips.

26. In a machine of the class described, the combination of notched card gripper heads, an assembling member having inclined and grooved guide members for receiving notched strips, mechanism for reciprocating the gripper heads over said assembling member, means for depressing the gripper heads to bring the notched cards into interlocked relation with the notched strips, and means co-acting with said guide members to straighten them up in substantially vertical position when the cards are being assembled with the strips.

27. In a machine of the class described, the combination of gripper head guides, vertically movable and horizontally reciprocable gripper head carriers, gripper heads rotatably mounted in said gripper head carriers and having jaws adapted to grip individual notched cards, co-acting means on said gripper head guides and gripper heads for partially rotating said gripper heads, an assembling member having channels for receiving notched strips, and guide bars extending from said gripper head guides over said assembling member and adapted to hold said gripper heads against rotation, said gripper heads cooperating with said assembling member to assemble the notched cards and notched strips into interlocked relation.

28. In a machine of the class described, the combination of vertically movable and horizontally reciprocable gripper heads having notched card gripping jaws, means for lock-

ing the jaws upon the cards, an assembling member having channels for receiving notched strips, mechanism for reciprocating the gripper heads over the assembling member and depressing the gripper heads to bring the notched cards into interlocked relation with the notched strips, a conveyor over which the completed article is moved by the gripper head reciprocating means, and means for unlocking the jaws of the gripper heads at a point over said conveyor.

29. In a machine of the class described, the combination of vertically movable and horizontally reciprocable gripper heads having jaws adapted to grip notched cards, an assembling member having channels in which notched strips are received, means for reciprocating the gripper heads over the assembling member and depressing the gripper heads to bring the notched cards into interlocked relation with the notched strips, strip severing means for severing the assembled strips from the remainder of the strips, and jaw opening means for said gripping heads arranged to open the jaws upon the return strokes of the gripper heads after the articles have been assembled.

30. In a machine of the class described, the combination of mechanism for feeding two sheets of material edge to edge, mechanism for cutting one sheet endwise and the other sheet crosswise in a manner to produce a plurality of notched strips, mechanism for turning all the strips through 90 degrees with those in each set in parallel planes, and mechanism for transporting one set of strips to a position opposite the other and then advancing one toward the other whereby to interlock all the strips into the form of a filler.

31. In a machine of the class described, the combination of means for feeding in parallelism two sheets of material in coincident planes, means for punching and cutting the two sheets into two sets of notched strips, and means for turning the strips on edge and for shifting the one set to a position opposite the other set preliminary to an assembly of the strips into a filler.

32. In a machine of the class described, the combination of means for gripping edge notched cards and holding them in a flat condition parallel with each other with the cards projecting from the gripping means, an assembling device having a holder for edge notched strips in parallel relation, means for moving the gripping means to a position directly opposite the assembling device, and mechanism for depressing the gripping means to bodily advance the notched cards into interlocked relation with the notched strips in the holder.

33. In a machine of the class described, the combination of gripping means for edge gripping notched cards and holding them in a flat condition parallel with each other with

- the cards projecting from the gripping means, an assembling device having holding means for holding edge notched strips in parallel relation, mechanism for moving one of said means to a position directly opposite the other means, and mechanism for moving one of said means toward the other to bodily advance the notched cards and strips into interlocked relation. 5
- 10 34. In a machine of the class described, the combination of means for feeding two sheets of material along two parallel paths, means for cutting the two sheets in one operation for each sheet into two sets of edge notched strips, means for turning both sets of notched strips around through 90° into parallelism and means for transporting one set of strips to a position opposite the other set with the notches of one aligned with the notches of the other and then bodily advancing one set towards the other to interlock the several strips into the form of a filler. 15
- 15 35. In a carton filler machine, assembling mechanism having relatively movable holders, the one being moved toward and away from the other, and in which two sets of edge notched pieces are brought together in interlocked relation in one operation of the holders. 20
- 20 36. In a carton filler machine, assembling mechanism having relatively movable holders for holding two sets of notched pieces, and mechanism for moving one of said holders across and towards the other holder whereby the notched pieces are brought together in interlocked relation in one operation. 25
- 30 37. In a machine of the class described, the combination of means for feeding filler material, mechanism for forming and cutting two sets of edge notched pieces from said material in which the notches of the pieces of one set have diverging side edges whereby when assembled with the other pieces the latter may tilt in the notches of the pieces of the first set, assembling mechanism having holders in which the two sets of notched pieces are held with one set disposed in inclined planes transversely of the other, and operating 35 means for transferring one set of pieces to the other in interlocked relation therewith. 40
38. In a carton filler machine having means for forming edge notches in one set of filler strips in which another set of notched filler strips may tilt from parallel to diverging positions, assembling mechanism having holders for the strips, one holder being arranged to hold strips therein in planes that are inclined with respect to the strips held in the other holder, and means for advancing one holder and therewith one set of notched strips towards the other and transversely thereof to effect interlocking engagement between the two sets of notched pieces. 45
- 60 39. In a machine of the class described, as- 50
- sembling mechanism for two sets of notched pieces, comprising holders for holding the two sets of notched pieces with the pieces of one set disposed crosswise of the pieces of the other set, the holder for one set of pieces being arranged to initially hold the pieces therein in inclined planes, means for moving one of the holders toward the other one to bring the two sets of notched pieces into an interlocked relation, and means acting simultaneously with said movement for moving the inclined pieces into parallel relation. 55
40. In a machine of the class described, an assembling mechanism comprising holders for holding two sets of notched pieces with the pieces of one set disposed crosswise of the pieces of the other set, the holders for one set of pieces being arranged to initially hold the pieces therein in inclined planes, means for moving one of said holders toward the other to thereby bring the notched pieces into interlocked relation, and means on one holder co-acting with means on the other holder for moving the pieces held in the last mentioned holder into parallel relation during the movement of one set of pieces towards the other. 60
41. In a machine of the class described, into which a sheet of filler material is fed, the combination of sheet slitting knives for slitting said sheets into strips, a member of an assembling mechanism having holders for holding said strips in planes that are inclined with respect to the sheet, and feed mechanism for feeding the strips to said holders, said feed mechanism having strip guiding inclined channels. 65
42. The method of making a filler which consists in feeding two sheets of material side by side, in cutting both sheets into strips having edge notches, in turning all the strips around through 90° with the strips from one sheet arranged at right angles to those formed from the other sheet, in transporting one set of strips to a position opposite the other set with the notches of one aligned with the notches of the other, and in advancing one set of strips toward the other whereby to interlock all the strips into the form of a filler. 70
43. The method of making a filler which consists in feeding two sheets of material side by side, in slitting one sheet endwise into strips having edge notches, in cutting the other sheet crosswise to provide strips having corresponding edge notches, in turning all the strips around 90° from a common plane into parallelism, in transporting one set of strips to a position opposite the other set with the notches of one aligned with the notches of the other, and in advancing one set of strips towards the other whereby to interlock all the strips into the form of a filler. 75
44. The method of making a filler which 80

- consists in feeding two sheets of material, in cutting from both sheets a plurality of strips having edge notches, in turning all the strips around through 90° with the strips from
- 5 one sheet arranged angularly with respect to those formed from the other sheet, in transporting one set of strips to a position opposite the other set with the notches of one aligned with the notches of the other, and
  - 10 in advancing one set of strips toward the other whereby to interlock all the strips into the form of a filler.

45. The method of forming a filler which consists in cutting from filler material two sets of notched pieces, in turning all of the pieces around through approximately 90° with the pieces of one set arranged transversely with respect to those of the other set, in shifting one set of pieces out of the plane
- 15 of the other set of pieces, in transferring one set of pieces to a position opposite the other set with the notches of one set aligned with the notches of the other set, and in advancing one set of pieces toward the other
  - 20 set whereby to interlock all of the pieces into the form of a filler.

In testimony whereof, I have hereunto set my hand this 1st day of April, 1929.

E. JOSEPH KANABAY.
